UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR FORMING OR SHAPING THE UPPERS OF BOOTS AND SHOES.

Application filed July 30, 1917, Serial No. 183,502. Renewed September 6, 1921. Serial No. 498,926.

To all whom it may concern:

Be it known that I, MATTHIAS BROCK, a citizen of the United States, residing at Boston, in the county of Suffolk and State 5 of Massachusetts, have invented certain Improvements in Machines for Forming or Shaping the Uppers of Boots and Shoes, of which the following description, in connection with the accompanying drawings, is a 10 specification, like reference characters on the drawings indicating like parts in the several figures.

This invention relates to machines for forming or shaping the uppers of boots and 15 shoes and particularly to machines for shaping or molding the heel end of a stitch-down shoe upper and forming thereon an outturned sole attaching flange. One type of machine for this purpose is shown and described in United States Letters Patent No. 20 1,160,135, granted on my application November 16, 1915.

An object of this invention is to provide an improved machine of this general type 25 which will be convenient, expeditious and effective in operation and simple in construction.

An important feature of this invention consists in a novel organization of means 30 for shaping the sides and an end portion of a shoe upper, with means for forming thereon an outturned flange, and operating means therefor by which the flange forming means is normally in an out-of-the-way position 35 to allow the operator free access to the shaping means so that the upper may be easily inserted therein.

As herein shown, the mechanism is adapted 40 for operating upon the rear portion of a shoe upper properly to shape the same, whether or not the upper includes a molded or unmolded counter, and to form thereon an outturned flange. The illustrated flange forming means is arranged to be moved 45 from its normal position to a position over the shaping means out of contact with the shoe upper, but within the confines of the margin of the upper left upstanding above the shaping means, and is then lowered into 50 substantial contact with the shaping means and moved toward the rear of the shoe to form the upstanding margin into an outwardly directed flange.

A further feature of the invention con-

sists of a flange turner of novel construction comprising, as shown, a narrow portion of less width than the heel seat, which portion first engages the upstanding upper and forms it outwardly at the rear end of the shoe, and a relatively wide portion wider than the heel seat which portion forms outwardly the side portions of the upstanding upper. The wide portion is preferably formed with a recess having a continuous wall extending about the heel seat portion, and the operating means is constructed and arranged to further depress the flange turner when the recess is located over the heel seat to bend the outturned flange beyond the position parallel with the heel seat which the flange is made to assume by the previous movement of the flange turner. Preferably the rear end shaping means is provided with a beveled upper face which cooperates with the continuous wall of the recess in the flange turner, powerfully to compress the outturned flange to cause it to set in its position at a downward directed acute angle to the plane of the heel seat. The wall of the recess in the flange turner is preferably inclined to fit the beveled face of the shaping means.

A further feature of the invention consists in a novel shaping means or mold for the rear portion of the upper comprising a readily changeable, inner or male member and outer or female members which comprise a portion which is brought against the rear portion of the upper to hold it against the inner member, and side portions which are progressively closed from the rear forwardly to force the upper against the side of the inner member.

As shown herein, the side portions are provided with segmental guides pivoted thereto and lying in grooves formed in the end portion to guide the side portion for closing movement about the joint between the end portion and the side portions.

A further feature of the invention consists in novel means for gaging the height of the upstanding margin which is constructed and arranged to be moved manually into operative position to gage the upper and to be moved automatically out of gaging position when the flange forming means is moved over the shaping means.

These and other features of the inven-

tion will appear more fully from the following detailed description when read in connection with the accompanying drawings and will be defined in the appended claims.

5 Fig. 1 is a side elevation of the machine;

Fig. 2 is a front elevation of the machine, parts being broken away;

Fig. 3 is a view of the flange turning and pressing member;

10 Fig. 4 is a plan view of the machine partly in section; and

Figs. 5, 6, 7 and 8 are side views, partly in section, of parts of the machine showing successive stages of their operation upon a 15 shoe.

Referring to Fig. 1, the frame of the machine is represented at 2 in which is mounted a driving shaft 4 carrying a drive wheel 6. Between the shaft 4 and the driving 20 wheel 6 suitable clutch mechanism is provided which is normally inoperative to drive the shaft. A treadle 8 is connected by a rod 10 to clutch controlling mechanism and is so arranged that when the treadle is depressed 25 the clutch will be thrown in and the machine will be operated.

On the shaft 4, Fig. 2, is a pinion 12 meshing with a large gear wheel 14 on a cam shaft 16 on which are mounted the various 30 cams from which the operative movements of the machine are derived. The machine as shown in Figs. 2 and 4 is duplex, two substantially similar molding mechanisms one for shaping the upper of a right shoe 35 and the other for shaping the upper of a left shoe, being arranged to be driven from the same cam shaft 16, the timing of the two mechanisms being such that when the molds of one are closed the molds of the other are open. Since the two mechanisms are otherwise alike, it will be necessary to describe 40 only one of them in detail.

Referring again to the clutch mechanism, the rod 10 is connected to a dog 11, pivoted 45 at 13 to the frame, which engages a toothed wheel 15 and disconnects the wheel 6 from the shaft 4 in a well-known manner, the springs 17 being then put under tension. Depression of the treadle 8 lifts the dog 11 50 out of engagement with the toothed wheel 15, and the springs 17 throw in the clutch, causing the shaft 16 to revolve and with it a cam block 18. The pivot shaft 13 of the dog 11 has an arm 19 carrying a roll which 55 engages the edge of the cam block 18 which is provided with two depressions 21, 23. After the machine starts the depression 21 passes beyond the roll on the arm 19 and the dog 11 is held out of engagement with 60 the toothed wheel 15 (pressure on the treadle being, of course, released) until the depression 23 reaches the roll, whereupon the dog 11 will engage the wheel 15 and cause the machine to stop.

65 An inner or male mold 20 is supported on

a member 22 secured to the frame 2 at 24. The shape of the member 22 is such that an upper of any height may be placed in inverted position with its heel portion about the male mold 20 and free space is provided 70 on all sides of the male mold for manipulation of the upper. The male mold is shown in plan in Fig. 4. Preferably one of the molding mechanisms is equipped with a mold for a right shoe upper and the other 75 with a mold for a left shoe upper.

A female mold is arranged to move forwardly and close about the male mold. The female mold comprises a central member 30, and side members 32, 34 arranged to move 80 about their lines of junction with the central member 30. Each of the side members 32, 34 has pivoted to it on its lower face a segmental piece 36 which slides in a correspondingly formed guideway in the central member 30. The centers of curvature of the pieces 36 lie in the joints between the member 30 and the side members; that is, in the points of junction of their inner faces. The central member 30 is connected by a pin 38 85 to a slide 40 which is mounted for limited movement by a pin and slot 41, 43, Fig. 5, in a carrier 42 and is backed up by a stiff spring 44, Fig. 4. The carrier is mounted for forward and rearward movement in the frame and is connected by a link 46 to a lever 48 (Fig. 1) fulcrumed to the frame 2 on a shaft 50 and actuated by a lever 52 to which it is connected by a link 54. The lever 52 is fulcrumed to the frame 2 at 56 and carries 90 between its ends a roll 58 which engages a cam path 59 in the outer side of the cam block 18 (Fig. 1). When the carrier 42 is given a forward reciprocation the mold members 30, 32, 34 advance toward the male mold and the side members 32, 34 are closed against the male mold by the action of rolls 61, Fig. 4, the axes of which are fixed in the machine frame, upon inclined levers 62 95 fulcrumed at 63 to the carrier 42. When the carrier and levers 62 are advanced the inclined outer faces of the levers engage the rolls 61 causing the inner faces of the rear end of the levers to press on spring plungers 64 mounted in each of the mold members 32, 34, and to close them yieldingly toward the mold 20. It will be noted that the molds are not fully closed until the outer mold members 32, 34 have fully embraced the 100 mold 20 and the rear portion 30 of the outer mold has engaged the upper on the mold 20 and also that the closing of the side portions 32, 34 occurs from the rear, where they join the part 30, forwardly toward the ends 105 of the counter. This action causes the upper to be brought progressively into contact with the inner mold from the rear portion forwardly until all parts are pressed forcibly 110 against the inner mold 20. The outer molds 115 have their upper faces downwardly and out 120

125 130

wardly inclined away from the inner mold for a purpose to be described. Above the molds is mounted for vertical movement a cross head 70. Vertical rods 72 are mounted 5 for longitudinal movement in the frames 2 and pass through the cross head 70. The rods are reduced at 73 to provide bearing shoulders for the cross head which cause it to be raised positively by upward movement 10 of the rods, and springs 74 are arranged on the rods between the upper face of the cross head and stop nuts 75 on the upper ends of the rods to render the downward pressure of the cross head yielding and adjustable. 15 The lower ends of the rods carry pins 76 which engage slots in the forward ends of arms 78 formed integral with a sleeve 80 mounted to rock on a shaft 82 mounted in the frame 2. The sleeve 80 has a rearward 20 arm 84 carrying a roll which lies in a cam path 86 formed in a cam block 88 on the shaft 16. Through the mechanism described, the head 70 is moved vertically toward and from the molds 20, 30, 32, 34.

25 A slide 90 is mounted in grooves 92 in the head 70 for movement rearwardly out of position over the molds and forwardly into position over the molds. To actuate the slide 90 a link 96 (Fig. 1) is connected to its rear 30 end and to an angle lever 98 pivoted to the machine frame at 50. Another link 102 is connected between the lever 98 and a lever 104 pivoted to the frame at 106 and having between its ends a cam roll 108 engaging a 35 cam path 110 formed in the right hand face of a cam block 60.

On the lower face of the slide 90 is secured a flange turning and pressing member 112 which has the form best shown in 40 Fig. 3 which is a perspective view showing its lower face in which is a recess 113 formed to co-operate with the beveled, that is the downwardly and outwardly inclined, upper faces of the mold members 30, 32, 34. 45 The member 112 is held to the slide 90 by a headed stud 114, the head of which engages a T-slot 116 formed in the upper side of the pressing member, and by a screw stud 118 having a reduced end which enters a 50 hole in the member. By turning the screw stud 118 up out of the hole in the member 112 the member may be removed from the headed stud 114 and another member of different size or shape introduced in place 55 of it. A gage 120 is provided to determine the amount of upper which will project above the molds. The gage is shown in operative position in Fig. 5 and consists of an L-shaped member pivoted at 122 to the cross head 70 and having a transverse portion 123 adapted to engage the edge of the upper forwardly of the part which contacts with the gage near the angle of the part 120. The gage 120 is held in inoperative position by a spring plunger 124 which 60 engages a depression in the end of the gage and holds it frictionally in the position shown in Fig. 6. When the slide 90 moves forward it engages the gage 120 and turns it from the position shown in Fig. 5 to the 70 position shown in Fig. 6 where it is yieldingly held by the spring plunger 124 until again required for use.

The mechanism has now been sufficiently 75 described so that the operation of the machine may be readily understood. When the machine is at rest the parts are positioned as indicated in Fig. 5 except that the gage 120 will be in inoperative position as shown in Fig. 6. The rear portion of a 80 shoe upper is placed about the inner mold 20, to which the operator has free access on all sides the gage 120 is swung down into operative position and the upper adjusted on the inner mold so as just to contact with 85 the gage, the width of the portion of the upper which is to be molded into an out-turned flange being thereby determined. After the upper has been adjusted properly 90 upon the inner mold the treadle 8 is depressed and the power operation of the machine commences. The slide 42 is moved toward the shoe and the mold member 30 is brought yieldingly against the rear part 95 of the upper, the side portions 32 and 34 at the same time embracing and closing upon the upper and conforming it forcibly to the contour of the inner mold. The slide 90 is now advanced to the position shown in Fig. 6 where the rear end 115 of the member 112 is above the heel portion of the upper. The cross head 90 next descends and carries the member 112 to a position inside the 100 upstanding margin of the upper and in contact with the inner mold 20, as shown in Fig. 7. The slide 90 is then moved rearwardly and the narrow rear portion 115 of the flange turning member 112 engages the rear portion of the upper and turns it outwardly 105 over the rear of the outer mold member 30. Continued movement of the slide causes the wide portion of the member 112 to engage the side portions of the upstanding upper and turn them outwardly over the side members 32, 34 of the outer mold. At the point 110 in the rearward movement of the slide 90 where the recess 113 of the member 112 is over the heel portion of the upper a dwell in the cam path 110 causes the slide to stop and the cross head is caused by the cam path 86 in the cam block 88 to move further 115 downwardly and cause the walls of the recess 113 to force the outturned flange of the upper against the outwardly and downwardly inclining upper faces of the outer mold members. The molds now having completely closed to hold the upper in molded position, the machine stops to give the upper time to set. Meantime the molds on 120 the other side of the machine have opened 125 130

and another upper may be introduced into them while the upper in the first molds is setting. When the machine is restarted the second set of molds will close and the first set open to release the molded upper.

Having fully described my invention, what I claim as new and desire to secure by Letters Patent of the United States is:

1. In a machine of the class described, means for molding the heel end of a shoe upper arranged to leave a marginal portion thereof projecting outside said means, means for forming a flange from said projecting margin, said means when inoperative being out of position over said molding means, means for moving the flange forming means over said molding means, means for relatively moving the molding means and the flange forming means to locate the flange forming means inside the projecting margin of the upper, and means for then moving the flange forming means rearwardly to form the projecting margin of the upper into an outwardly directed flange.
2. In a machine of the class described, means for molding the heel end of a shoe upper arranged to leave a marginal portion of the upper projecting above said molding means, means for forming a sole attaching flange from said marginal portion, means for moving the flange forming means first downwardly inside the upstanding margin, and means for then moving the flange forming means longitudinally toward the rear portion of the upper, the flange forming means being shaped first to form outwardly the margin at the rear of the shoe upper and then to form outwardly the margin of the shoe upper at the sides.
3. In a machine of the class described, means for molding the heel end of a shoe upper comprising a male mold having the shape of the rear portion of a shoe, and a three-part female mold, means for moving the central part of the female mold against the rear part of an upper on the male mold, means for closing the other parts of the female mold against the sides of the upper, and means for bending the margin of upper extending above the mold over against the top face of the female mold.
4. In a machine of the class described, inner and outer molds for molding the heel end of a shoe upper arranged to leave a marginal portion of said upper projecting beyond said molding means, and a flange former comprising an integral member having a rearwardly extending laterally narrow portion to turn outwardly the rear portion of the upstanding margin over the outer mold and a laterally wide portion having formed therein a recess adapted to receive the upper portion of the outer mold and to form the outturned margin of the upper against the top face of the outer mold.

5. In a machine of the class described, means for molding the heel end of a shoe upper arranged to leave a marginal portion of the upper projecting beyond the said molding means, means for bending outwardly the projecting marginal portion of the upper over the outer mold, said means having a recess provided with a continuous wall to act upon the outturned flange which has been laid over the top face of the outer mold.

6. In a machine of the class described, an inner mold having the shape of the rear portion of a shoe upper, an outer mold adapted to close upon the inner mold and having a downwardly and outwardly beveled top face, a flange turning and forming member constructed first to turn outwardly the rear portion of the margin and then to turn outwardly the side portions of the margin and having a recess with continuous edge walls complementary to the beveled top face of the outer mold, and means to force the flange forming member downwardly after its turning action to form the flange against the top face of the outer mold.

7. In a machine of the class described, an inner mold, an outer mold arranged to close about the inner mold and comprising a single central portion and side portions, means for effecting yielding pressure of the central portion against the rear end of the inner mold, and means for progressively closing the side portions from the rear forwardly against the inner mold with yielding pressure.

8. In a machine of the class described, an inner mold, an outer mold arranged to close about the inner mold and comprising a central portion and side portions, and segmental members pivoted to the side portions and occupying slots in the central portion, said members guiding said portions for movement about the joint between the central portion and the side portions.

9. In a machine of the class described, an inner mold, an outer mold arranged to close about the inner mold and comprising a central portion and side portions, and segmental members between the side portions and the central portion to guide said portions for relative movement about the joints between them.

10. In a machine of the class described, an inner mold, an outer mold arranged to close about the inner mold and comprising a central portion and side portions, and segmental members between the side portions and the central portions to guide said portions for relative movement about the junction line of their inner faces.

11. In a machine of the class described, an inner mold having the shape of the rear portion of a shoe upper, an outer mold adapted to close upon the inner mold, a carrier for the outer molds, means for mov-

- ing the carrier, and mold closing means comprising rearwardly directed arms each pivoted at one end to the carrier and engaging the molds at their opposite ends, 5 and means for effecting movement of the arms toward each other to close the molds when the carrier is moved.
12. In a machine of the class described, an inner mold having the shape of the rear portion of a shoe upper, an outer mold adapted to close upon the inner mold, a carrier for the outer molds, means for moving the carrier and mold closing means comprising rearwardly directed arms each 10 pivoted at one end to the carrier and engaging the molds at their opposite ends, and rolls on stationary axes for effecting movement of the arms toward each other to close the molds when the carrier is moved 15 toward the inner mold.
13. In a machine of the class described, an inner mold having the shape of the rear portion of a shoe upper, an outer mold adapted to close upon the inner mold, a carrier for the outer molds, means for moving the carrier, and mold closing means comprising rearwardly directed arms each pivoted at one end to the carrier and engaging the molds at their opposite ends, 20 spring pressed plungers between the arms and the molds, and means for effecting movement of the arms toward each other when the carrier is moved toward the inner mold.
14. In a machine of the class described, the combination of upper shaping means, flange forming mechanism, and a gage carried by said mechanism and having an operative and an inoperative position, the gage 25 serving when in operative position to determine the amount of projection of the upper beyond the shaping means and arranged to be moved into inoperative position by movement of the flange forming mechanism.
15. In a machine of the class described, the combination of upper shaping means, flange forming means, a cross head on which the flange forming means slides into and 30 out of position over the shaping means, a gage mounted on the cross head and arranged for manual movement into position over the shaping means to gage the projection of the upper above said means, and means for automatically moving the gage 35 out of gaging position during the operation of the flange forming means.
16. In a machine of the class described, the combination of upper shaping means, flange forming means, a gage for the upper 40 constructed and arranged to engage the edge of an upper positioned in the shaping means at the rear end of the upper and also to engage the upper forwardly of the rear end to determine the width of the upper to be formed into a flange by the flange 45
- forming means entirely around the flanged portion, and means for moving the gage out of gaging position as an incident to the operation of the machine.
17. In a machine of the class described, 70 a cross head having a headed stud, a flange former having a T-slot to engage the stud, and means for preventing movement of the flange former in the plane of the head of the said stud.
18. In a machine of the class described, 75 an inner mold, an outer mold constructed and arranged to close upon the inner mold, a carrier for the outer mold, means for moving the carrier, yielding plungers 80 mounted in the outer mold, levers pivoted to the carrier at one end and resting against the plunger at the other end, said levers being normally inclined with reference to the direction of movement of the carrier, 85 and rolls on stationary axes arranged to engage the levers when the carrier is moved and to cause the outer mold to be closed upon the inner mold.
19. A machine for molding the rear portion of upper materials having, in combination, inside and outside formers and operating mechanism therefor, flange turning means, a slide carrying the flange turning means movable bodily over the formers, a vertically movable head in which said slide is mounted, and operating mechanism to advance the slide to carry the flange turning means over the formers, to depress the head 90 to bring the flange turning means into operative relation to the upper materials, to move the slide rearwardly to cause the flange turning means to operate on the upper, and further to depress the head to apply molding pressure to the flange. 95
20. In a machine for shaping the rear end of a shoe upper and flanging the upper outwardly, the combination of a rigid, stationary support, an inner mold on the support, an outer mold to shape the upper and 100 leave the margin of the upper projecting beyond the molds, a flange turner, and means for giving the flange turner a four-motion movement, first over the inner mold out of contact with the upper, then down into contact with the inner mold, then rearwardly 105 to form the flange and finally to initial position. 110
21. A machine for shaping the upper materials of the end portion of a shoe having, 115 in combination, means for shaping the upper and leaving the margin of the upper extending beyond said means, a flange former having an initial position remote from the upper out of contact therewith and outside of the confines of the margin, means for relatively moving the former and shaping means to bring the former inside of the extending upper materials, and means for then relatively moving the shaping 120 means. 125
- 130

means and former to cause the former to act on the margin of the upper.

22. In a machine of the class described, the combination of means for shaping the side and end portions of an inverted shoe upper, means for forming on the upper an outturned flange, operating means for the flange forming means constructed and arranged to position the flange forming means normally in an out of the way position outside of the confines of the upper to allow the operator free access to the shaping means for inserting the upper therein, and means for operating the flange forming means to flange the upper.

23. A machine for molding the rear portion of upper materials having, in combination, inside and outside forms operating to mold the rear portion of the upper and leave a margin extending beyond the molds to be formed into a flange, flange turning means, a slide carrying the flange turning means movable bodily over the formers, a vertically movable head in which said slide is mounted, and operating mechanism to advance the slide to carry the flange turning means over the formers, to depress the head to bring the flange turning means into operative relation to the upper materials to move the slide rearwardly to cause the flange turning means to operate on the upper and to further depress the head to apply molding pressure to the flange, said mechanism being constructed and arranged to stop with the flange turning means in depressed position with the flanges under molding pressure and upon restarting of the machine to return to initial position.

24. In a machine for shaping the rear end of a shoe upper and flanging the upper outwardly, the combination of a stationary support, an inner mold on the support arranged to afford free access to the mold at the top and sides, an outer mold normally located at the rear of the inner mold and arranged to advance and close on the inner mold to shape the upper and leave the margin of the upper projecting beyond the molds, a flange turner, means for giving the flange turner a movement over the inner mold out of contact with the upper, then down into contact with the inner mold, then rearwardly to form the flange, and means to stop the machine with the flange turner in flange pressing position.

25. A machine for shaping the upper materials of the end portion of a shoe having, in combination, means for shaping the upper and leaving the margin of the upper extending beyond said means, a flange former having an initial position horizontally removed beyond the confines of said margin, means for relatively moving the former and

shaping means to bring the former inside the margin of the upper materials, and means for then relatively moving the shaping means and former to cause the former to act on the upper margin.

26. In a machine of the class described, the combination of means for shaping the side and end portions of a shoe upper, means for forming on the upper an outturned flange, operating means for the flange forming means constructed and arranged to position the flange forming means normally in an out of the way position at the rear of the shaping means to allow the operator free access to the shaping means for inserting the upper therein, and to move the flange forming means forwardly, downwardly and rearwardly to flange the upper.

27. In a machine for molding the rear portion of shoe upper materials, the combination of inside and outside formers, operating means therefor to shape the side and end portions of the upper and present a margin in upstanding position about the inside former, flange forming means movable bodily to flange the margin outwardly beyond the inside former, means for operating the flange forming means to move it over, down inside the upstanding margin and rearwardly to flange the upper, and separate means for applying, through the flange forming means, a molding down pressure to the flange.

28. In a machine of the class described, the combination of upper shaping means, flange forming mechanism, and a gage having an operative position spaced above the shaping means and an inoperative position, the gage serving when in operative position to determine by contact with the edge of the upper the amount of projection of the upper beyond the shaping means and arranged to be moved lengthwise of the shaping means into inoperative position upon movement of the flange forming mechanism.

29. In a machine of the class described, the combination of upper shaping means, flange forming mechanism, a cross head on which the flange forming mechanism slides into and out of position over the shaping means, and a gage arranged for horizontal movement into gaging position above the shaping means to determine by contact with the edge face of the upper the amount of projection of the upper above said means, said gage being constructed and arranged to be reversely moved automatically out of gaging position during forward movement of the flange forming mechanism.

In testimony whereof I have signed my name to this specification.

MATTHIAS BROCK.
